OSCAR CHRISTIANSEN, OF ST. PAUL, MINNESOTA, ASSIGNOR TO OSCAR S. RISVOLD, OF ST. PAUL, MINNESOTA

GAME

Application filed August 17, 1931. Serial No. 557,579.

My invention relates to game devices in general and more particularly to a game board involving the use of two sets of so-called "men" identified by size and certain numbers and movable on the surface of a game board with certain design and lines governing the movements of the respective sets of men. The main object of the game is to provide an interesting and enjoyable pastime requiring considerable study by the contestants, as hereinafter fully set forth and illustrated in the accompanying drawing, in which,—

Fig. 1 is a top or face view of my game board alone in its preferred design.

Fig. 2 is a view corresponding to Fig. 1 but showing the sets of men on the board in their initial positions preparatory to starting the playing of a game.

Fig. 3 is a lower edge view of Fig. 2 showing the board lying on a flat surface.

Fig. 4 is a face view of the game, colors being omitted, and illustrating a completed game, with a set of 13 men of one contestant in positions indicating a game won by one of the contestants using the secondary blocks or men designated B.

Referring to the drawing by reference letters and numerals, I will first describe the preferred design of board, then the movable men and their movements and finally the rules and positions determining the winner of the game.

The board is preferably square and designated 5 and on the upper face of which is a vari-colored design comprising a round central field 6, shown red, and said central field surrounded by a ring-shaped field 7, shown blue, and exteriorly of which is a comparatively wide ring-shaped field 8, shown white. Exteriorly of ring 8 the board may be colored uniformly, as blue, to the four corners. Fields 6 and 7 are crossed by two lines 9 crossing each other at its center and on which lines are a number of spots 10 in predetermined uniform spacing and radiating from the center to the circular line 11 separating fields 6 and 7. These spots are preferably 13 in number, one at the center and 3 on each line outwardly of the said center.

In the white field 8 I make a number of straight lines converging in pairs at the outer circle of said field and spreading inwardly therefrom in pairs to meet adjacent spread lines at the inner circle of the field, forming in effect an eight-point star with spots 10A at their tips and bases and like spots intermediate the other ones on each line. On the circle separating field 7 and 8 are more spots 10B, one at the center of the base of each star-point. Therefore on the complete design there are 48 spots exteriorly of the 13 central spots designated 10.

In the drawing N, E, S and W designate for convenience the north, east, south and west sides of the board. Two players facing the board from opposite sides will hereinafter be designated respectively as player N and player S.

As previously stated the game is played with two sets of blocks or men, one set comprising 48 men designated A played by N and the other set comprising only two men designated B played by S. Both sets may comprise small blocks, discs, buttons or the like, the two men of player S each bearing a number 50, arbitrarily, the total value of the two therefore being 100 points, and to start the game these two men are placed on spots 10 one position outwardly of the center on the same line 9 (see Fig. 2). The 48 men A are preferably smaller than the B men and each bears a relatively small number, the total value of all the A men calculated to be best set at 250.

It will be understood that N and S play alternately, N starting and the only possible move is one of the four A men at the outer extremities of the lines 9 moving it inwardly toward the center. N's object in the game is to get 13 of his A men on the 13 spots in the center field, his moves being always from one position to the next. It is important that S should block every effort of N to get the 13 A blocks or men filling up the center field and he has the privilege of jumping an A block if it is in such position that the B block can go over the A block and be set on an unoccupied spot beyond it, all such moves being permissible in straight lines or obtuse-angle line but not in an acute-angle path as

for instance from position 51—52—53 in Fig. 2. Any A block jumped over is forfeited and removed from the board. A further objective of N is to get 13 A's in the center field and the valuation of said blocks must be over 100 points for him to win the game. Obviously, N must maneuver his blocks so that the B blocks are and must be lured away from the center field in order to get a sufficient number of A blocks into the center field and yet not lose too many of the A blocks, one rule of the game being that the B blocks are always on the board, cannot be jumped over and are not forfeited in any play.

If N succeeds in getting 13 A blocks into the center field it does not necessarily indicate that the game is won by him, in fact if the 13 A blocks are not of over 100 points in value 20 N has lost and S has won the game.

In Fig. 4 a finished game is shown in which N has succeeded in placing 13 A blocks in the center field, the value of said blocks being 112 points. There are 7 other A blocks shown 25 in scattered positions. Thus with 13 A blocks in the center field and 7 others in the outer fields a total of 20 A blocks are on the board indicating that at the end of the game S had taken 28 of N's blocks during the playing of 30 the game.

A preferred rule is that all A blocks must move in lines leading to the crossed lines 10 and on the spots thereof, it being understood that all A blocks having entered the center 35 field must remain there and cannot be moved outward on lines 10. Actual playing of this game reveals many intricate plays, requiring forethought and anticipated future moves of opposite contestants. I have stated that A 40 blocks are moved from spot to spot progressively and of course always toward the center field. The B block movements are from spot to spot in any direction but always on a line, for example no move of a B block can 45 be made as from position 51 across to position 53 in Fig. 2.

The game is played preferably according to the rules and regulations above set forth. Variations in rules governing the movements 50 of the blocks may be made. Also the design of the playing area may be modified but the preferred arrangement of lines, fields and arrangement of spots has been clearly illustrated and plays thereon outlined above.

55 I claim:—

In a game of the class described, a flat playing board with its upper surface comprising the playing area; said area comprising a central field, an intermediate field 60 circling the center field and an outer field encircling the intermediate field, delineations on said playing area separating the respective fields, a pair of crossed straight lines intersecting the two innermost fields, pairs of 65 lines, each of said pairs being in V-formation

with the apex on the outer perimeter of the outer field and the opposite ends contacting with the adjacent lines on the perimeter of the intermediate field to form with said collective pairs of lines a multi-point star design, 70 spots on all said lines in predetermined spacing, two sets of blocks adapted to cover a predetermined number of said spots and movable in directions indicated by said lines, 75 said sets of blocks comprising one set of two blocks each with an arbitrary value indicated on it, and one set of a larger number of blocks with numerical designations thereon relatively smaller than the numerical designations of the first described set of blocks. 80

In testimony whereof I affix my signature.

OSCAR CHRISTIANSEN.
